UNITED STATES PATENT OFFICE.

HUGO KURTZNER, OF NEW HAVEN, CONNECTICUT.

SECTION FOR AUTOMOBILE-RADIATORS.

943,257.

Specification of Letters Patent. Patented Dec. 14, 1909.

Application filed June 9, 1909. Serial No. 501,163.

To all whom it may concern:

Be it known that I, HUGO KURTZNER, a citizen of the United States, residing at New Haven, in the county of New Haven and 5 State of Connecticut, have invented a new and useful Improvement in Sections for Automobile-Radiators; and I do hereby declare the following, when taken in connection with the accompanying drawings and 10 the numerals of reference marked thereon, to be a full, clear, and exact description of the same, and which said drawings constitute part of this specification, and represent, in—

Figure 1 a broken perspective view of a 15 portion of a radiator-section constructed in accordance with my invention. Fig. 2 a broken view in elevation on an enlarged scale showing the relative arrangement of the corrugated and shouldered plates before 20 their shouldered edges are dipped in solder. Fig. 3 a broken view in vertical section showing the tortuous water-passages formed between the plates placed back to back. Fig. 25 Fig. 4 a sectional view on the line *a—b* of Fig. 3. Fig. 5 a broken plan view of one of the plates in correct scale.

My invention relates to an improvement in sections for automobile radiators, the object being to provide a light, cheap, strong 30 and effective section.

With these ends in view my invention consists in a radiator-section having certain details of construction and combinations of parts as will be hereinafter described and 35 pointed out in the claim.

In carrying out my invention I place one upon the other in a predetermined order of arrangement, a number of thin sheet-metal transversely corrugated plates the semi-circular or substantially semi-circular corrugations 40 of which terminate at their ends in corresponding shoulders 3 struck on slightly larger circles than the corrugations. These plates are assembled face to face in pairs so 45 as to form horizontal tubular air-passages 4 between the concave faces of the plates and tortuous vertical contracting and expanding water-passages 5 between the convex faces of the plates as clearly shown in Fig. 3. The 50 said water-passages 5 are included between the said shoulders 3 which rest upon each other as shown in Fig. 2, and so prevent the convex faces of the plates from making contact with each other in the narrow portions 55 6 of the water-passages 5 which are so tortuous that the water will pass through them

so slowly that it will be exposed for a considerable length of time for the cooling effect of air passing through the air-passages 4. It will be observed by reference to Figs. 60 2 and 3 that in assembling the plates they are placed face to face in pairs, but that every alternate pair is moved upward or downward with respect to the adjacent pair, for a distance substantially represented by 65 half the diameter of the air-passages. In other words, the plates are staggered with reference to each other, in pairs so as to secure compactness of construction and to form tortuous passages for the water. After 70 the plates have been properly assembled their edges will be united by a binder of solder 7 which unites the plates together in a laminated cellular structure.

My improved construction is not only 75 light and cheap, but also extremely strong as the transverse corrugations of the plates make them stiff and resistant of blows tending to crush them. If desired the plates may be swaged after they have been assembled 80 and soldered together by the introduction of hexagonal swaging tools, the use of which will give the section the appearance of a honeycomb.

I claim:—

A section for automobile radiators, the 85 said section being composed of a number of independently formed transversely corrugated sheet-metal plates each extending from the top to the bottom of the section 90 and each formed upon each edge with a continuous shoulder slightly larger than the corrugations, and the said corrugations and shoulders being circular in form, the plates being symmetrically assembled face to face 95 in pairs so as to form circular horizontal air-passages, the pairs being assembled unsymmetrically so as to form tortuous vertically arranged contracting and expanding water-passages between the convex faces of the 100 plates which are held apart for the formation of these passages by means of the said shoulders, and the edges of the corrugations and hence the plates being bound together by a continuous sheet of solder. 105

In testimony whereof, I have signed this specification in the presence of two subscribing witnesses.

HUGO KURTZNER.
